(57) **CLAIM**

The ornamental design for an energy absorbing locking arm of a rope grab, as shown and described.

DESCRIPTION

FIG. 1 is a first side perspective view of an energy absorbing locking arm of a rope grab according to the present invention; FIG. 2 is a second side perspective view of the energy absorbing locking arm of a rope grab shown in FIG. 1; FIG. 3 is a front view of the energy absorbing locking arm of a rope grab shown in FIG. 1; FIG. 4 is a rear view of the energy absorbing locking arm of a rope grab shown in FIG. 1; FIG. 5 is a top view of the energy absorbing locking arm of a rope grab shown in FIG. 1; and, FIG. 6 is a bottom view of the energy absorbing locking arm of a rope grab shown in FIG. 1. The broken lines showing portions of the energy absorbing locking arm of a rope grab are for the purpose of illustrating portions that form no part of the claimed design.
